DUST SEPARATING FAN

Ernest A. Lundstrom, Wellsville, N. Y., assignor
to The Air Preheater Corporation, New York,
N. Y.

Application April 17, 1943, Serial No. 483,374

2 Claims. (Cl. 183—35)

The present invention relates to fluid displacing apparatus such as fans or pumps and particularly to improvements in the construction of a pump or fan arranged to have a double action effect on the fluid handled such as air, other gas or liquid.

The fluid displacing apparatus of this invention embodies a novel construction and arrangement for the impeller blades together with a novel disposition of the latter with respect to the housing enclosing the impeller so that a single stream of fluid may be twice acted upon by the impeller blades. The invention also contemplates the use of the apparatus as a dust separator when handling gas or air by providing it with collecting scoops positioned to catch dust and other particles separated under the action of centrifugal force.

For convenience of description the apparatus will be referred to in its aspect as a fan and the invention will be best understood upon consideration of the following detailed description of an illustrative embodiment thereof when read in conjunction with the accompanying drawings in which:

Figure 1 is a longitudinal sectional view through a centrifugal fan embodying the present invention and constructed to also function as a dust separator.

Figure 2 is an end view on a reduced scale of the fan and shows the arrangement of the outlets for the fluid;

Figure 3 is an end view and Figure 4 a side view of the impeller of the fan illustrated in Figure 1, some parts being broken away.

In the drawings the numeral 10 designates the shaft of a fan impeller driven by a motor 11 and provided with a hub 12. Rectangular, radially projecting blades 13 are attached near their inner corners to hub 12, the blades extending axially of the latter, or inclined somewhat in relation to the hub axis. The impeller is completely surrounded by a generally cylindrical housing 14 formed in one end wall with an opening 15 for admitting air or gas to the passages between the fan blades. The interior of housing 14 has two chambers 17, 18 located at opposite sides of an annular partition 20 disposed transversely of shaft 10 and extending from the outer wall 21 of the housing to a position closely adjacent the outer corners of the blades 13.

The two chambers 17, 18 into which the housing 14 is divided by partition 20 are sealed from each other at the junction between the partition and the edges of the fan blades by circumferen-

tially disposed sealing members 22, 23. These, as illustrated, comprise two rings rabbeted on their inner and outer peripheral faces, respectively, and interlockingly engaged. The ring 22 is formed on the inner face of the partition 20 while ring 23 is mounted about the impeller around the outer end edges of the blades 13. Rabbeted annular sealing members 36, 37 on the outer left hand corners of the impeller blades and opposite thereto on the inner face of the left hand end wall seal the chamber 17 from inlet 15 to prevent direct flow of fluid therebetween. The right hand corners of the blades are attached to a ring 38.

The chamber 17 has a tangentially disposed outlet 24 which is directed horizontally. The right hand end wall 41 is dished inwardly to the outer face of the hub disc beyond the inner edges of the blades 13 so that chamber 18 is a hollow torus. As described below the impeller is provided with two separate groups of passages 30 and 31 with the passages of one group alternating with those of the other. The opening 14 in the left hand end wall of housing 14 admits the stream of fluid, such as air, which then flows through the set of passages 30 of the impeller into chamber 18 and back through the other set of impeller passages 31 into chamber 17 and to outlet 24.

In the form shown herein to create two groups of passages 30, 31, alternate spaces between adjacent blades are closed at 32 and 33 along one pair of opposite edges while the intermediate spaces are closed at 34, 35 along the other pair of opposite edges. Thus the intermediate passages 31 lead from the inlet 15 at the left to the chamber 18 while the alternate passages 31 lead from chamber 18 at the right to chamber 17.

Inasmuch as the stream of fluid flows through passages 30 in a general upward and radially outward direction as the impeller rotates a centrifugal action is imposed thereon which becomes effective to throw particles of dust or other minute entrained material toward the inner wall surface of the end wall 41 of chamber 18, Fig. 3. Due to the abrupt change in direction of the fluids as it rounds the right hand corners of the blades in passing from passages 30 to enter adjacent passages 31, the centrifugal separating effect is accentuated. Accordingly, a series of annular collector scoops or guide vanes 40 are provided as shown in Fig. 3 projecting from the end wall 41 so that the disentrained particles which impinge on the rings are directed to a discharge outlet 42 at the bottom of the fan housing.

Although in the foregoing description the invention has been described as embodied in a fan

and although the term fan is used in the appended claims, it will be appreciated that its principles may be applied to pumps for handling liquids as well as gaseous fluids.

What I claim is:

1. In a centrifugal fan; an impeller comprising a hub; a plurality of polygonal axially and outwardly extending plates spaced circumferentially about and each abutting said hub adjacent one corner and attached to said hub; a housing surrounding said impeller and formed in one end wall with a fluid inlet at one side of the impeller; cooperating sealing means mounted on the outer corners of said plates and on the inner wall of said housing for dividing the interior thereof into a fluid inlet chamber at said one side of the impeller and into intermediate and outlet chambers surrounding said impeller; means closing the spaces between certain edges of adjacent plates so arranged as to form two groups of passages through the impeller with passages of one group alternating with those of the other, passages of each group communicating at adjacent ends with said intermediate chamber and the opposite ends of the passages of the two groups being radially spaced and communicating respectively with said inlet chamber and with said outlet chamber; means forming a fluid discharge outlet leading from said outlet chamber, whereby fluid entering into said inlet chamber passes through one group of impeller passages into said intermediate chamber and flows from the latter through the other group of passages to the outlet chamber; means forming a dust discharge outlet from said intermediate chamber; and annular scoops mounted in said intermediate chamber on the inner surface of the other end wall of said housing and facing said impeller for receiving dust centrifugally separated from air passing from one group of passages into the other and for directing it to said dust outlet.

2. In a centrifugal fan; an impeller comprising a hub; a plurality of polygonal axially and outwardly extending plates spaced circumferentially about and each abutting said hub adjacent one corner and attached to said hub; a housing surrounding said impeller and formed in one end wall with a fluid inlet at one side of the impeller; cooperating sealing means mounted on the outer corners of said plates and on the inner wall of said housing for dividing the interior thereof into a fluid inlet chamber at said one side of the impeller and two adjacent annular chambers surrounding said impeller and constituting an outlet chamber and an intermediate chamber; means closing the spaces between certain edges of adjacent plates so arranged as to form two groups of passages through the impeller with passages of one group alternating with those of the other, passages of each group communicating at adjacent ends with said intermediate chamber and the opposite ends of the passages of the two groups being radially spaced and communicating respectively with said inlet chamber and with said outlet chamber; means forming a fluid discharge outlet leading from said outlet chamber, whereby fluid entering said inlet chamber passes outwardly and axially through one group of impeller passages into said intermediate chamber and flows inwardly to passages between the lower edges of said plates and thence outwardly and axially through the other group of passages to the said outlet chamber; means forming a dust discharge outlet from said intermediate chamber; and annular scoops mounted in said intermediate chamber on the inner surface of the other end wall of said housing and facing said impeller for receiving dust centrifugally separated from air passing from one group of passages into the other and for directing it to said dust outlet.

ERNEST A. LUNDSTROM.
